UNITED STATES PATENT OFFICE.

JOHN W. SMITH, OF RENOVO, PENNSYLVANIA, ASSIGNOR OF ONE-HALF TO WILLIAM FORD, OF RENOVO, PENNSYLVANIA.

CAR COUPLER.

Application filed August 7, 1925. Serial No. 48,832.

This invention relates to a car coupler, the general object of the invention being to provide simple and effective means for enabling cars to be coupled and uncoupled 5 without the trainmen going between the cars.

Another object of the invention is to make the coupling action an automatic one, with spring actuated means for locking the 10 parts in coupled position.

A further object of the invention is to provide a manually rotatable shaft for moving the locking member to releasing position to uncouple the cars.

15 This invention also consists in certain other features of construction and in the combination and arrangement of the several parts, to be hereinafter fully described, illustrated in the accompanying drawings 20 and specifically pointed out in the appended claims.

In describing my invention in detail, reference will be had to the accompanying drawings wherein like characters denote 25 like or corresponding parts throughout the several views, and in which:—

Figure 1 is a plan view of two coupling elements.

Figure 2 is a similar view, but showing 30 the parts in uncoupled position.

Figure 3 is a vertical sectional view through one element, showing the parts in coupled position.

Figure 4 is a similar view, but showing 35 the parts in uncoupled position.

Figure 5 is a horizontal sectional view, with parts in plan.

Figure 6 is a section on line 6—6 of Figure 3.

40 Figure 7 is a section on line 7—7 of Figure 3.

Figure 8 is a section on line 8—8 of Figure 3.

Figure 9 is a view of the locking member.

45 Figure 10 is a view of the two-part shank of the coupling head.

As shown in these views, each draw bar 1 is of hollow construction and has its enlarged outer end of forked construction between the tongues of which is pivoted a substantially U-shaped coupling member 2, the member being so formed that it will have its outer limb engage the corresponding limb of another element when the two 50 come together, this action being caused by

the outer limb of each member striking the inner limb of the opposite member, which rocks the two members about their pivotal points, as will be seen from an inspection of Figures 1 and 2.

60 A bar 3 is pivoted to the inner limb of each member 2 and slides in the hollow draw bar 1 and has a bolt 4 pivoted to its inner end which is provided with a lower inclined shoulder 5 and an upper inclined shoulder 6.

The rear part of the draw bar is enlarged and has a cavity 7 therein, the front wall of which having an inclined part 8 thereon for engaging the shoulder 5 of the bolt when the same is in locking position and a locking member 9 is fastened to a 70 shaft 10 which passes through the chamber and said member is provided with an opening 11 for receiving the end of the bolt 4 and with an inclined part 12 for engaging the shoulder 6 for holding the bolt in locking position or in a position with the coupling member 6 closed.

A spring 13 tends to hold the member 9 in locking position and this spring engages a curved tubular part 14 formed on the member 9 and a curved socket 15 formed in the rear wall 75 of the chamber. Said wall has a slot 16 therein which communicates with the socket, so that the spring, or a part thereof, if the same should be broken, can be removed from the socket by a tool.

The tail part 17 of member 9 is provided with teeth which are engaged by the teeth of a pinion 18 on a shaft 19 which extends 80 across the end of the car and has a handle 20 thereon so that a trainman can rock the shaft, without passing between two cars, to move the member 9 to releasing position and against the action of its spring.

When 85 this member is so moved, a spring 21 will force the bar 3 forwardly to move the coupling element 2 to open position and this movement will pull the bolt forwardly out of engagement with the wall 8 and the locking member 11. This spring 21 engages

90 a projection 22 on the bar 3 and a clip 23 which has its ears 24 engaging slots 25 formed in the walls of an upper extension 95 26 of the bore of the draft bar.

100 From the foregoing, it will be seen that when two cars come together, the coupling member 2 on one car, striking the rear part of the coupling member on the other car, will swing the same to coupling position and 105

110

this movement will cause the bar 3 and the bolt 4 to move rearwardly so that the end of the bolt, striking the inclined part 12 of the locking member 9, will raise said member 9 against the action of its spring until the end of the bolt enters the recess 11, when the spring 13 will force the member 9 and the bolt downwardly so that the shoulders 5 and 6 of the bolt will engage the parts 8 and 12 and thus the coupling parts will be locked in coupling position. This action will also compress the spring 21. When the cars are to be uncoupled, the shaft 19 is rocked by a trainman through means of its handle 20 to raise the member 9 so as to free the bolt and then the spring 21 will move the parts forwardly into uncoupling position.

The parts are easily accessible so that new springs and other parts can be easily replaced if broken and the coupling action is entirely automatic.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:—

1. A car coupler, comprising a hollow draw bar, a coupling element pivoted thereto, a member slidably mounted in the draw bar and pivoted to the coupling element, a bolt pivoted to the sliding element and having a part engaging an inner wall of the draw bar, a pivoted member in the draw bar for engaging the bolt to hold the same in engagement with the wall, spring means for holding said member in holding position and manually operated means for rocking the member to release the bolt.

2. A car coupler, comprising a hollow draw bar, a coupling element pivoted thereto, a member slidably mounted in the draw bar and pivoted to the coupling element, a bolt pivoted to the sliding element and having a part engaging an inner wall of the draw bar, a pivoted member in the draw bar for engaging the bolt to hold the same in engagement with the wall, spring means for holding said member in holding position, manually operated means for rocking the member to release the bolt, and spring means for projecting the parts forwardly, after the bolt has been released to move the parts to uncoupling position.

In testimony whereof I affix my signature.
JOHN W. SMITH.
